(57) **CLAIM**

The ornamental design for a vehicle storage organizer as shown and described.

DESCRIPTION

FIG. 1 is a top, front, left side perspective view of a vehicle storage organizer showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded top, front, left side perspective view of the vehicle storage organizer, shown with the bottom section separated;

FIG. 10 is a top, front, left side perspective view of the vehicle storage organizer shown in a half-folded configuration;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 2;

and,

FIG. 14 is an enlarged view of portion 14 shown in FIG. 9. The dash-dash broken lines in the drawings depict portions of the vehicle storage organizer that form no part of the claimed design. The dot-dash broken lines represent boundaries of the enlarged portions and form no part of the claimed design.
